UNITED STATES PATENT OFFICE.

FRANK J. KOKAL, OF HERMINIE, PENNSYLVANIA.

BURGLAR ALARM.

Application filed October 17, 1924. Serial No. 744,234.

To all whom it may concern:

Be it known that I, FRANK J. KOKAL, a citizen of the United States, residing at Herminie, in the county of Westmoreland and State of Pennsylvania, have invented new and useful Improvements in Burglar Alarms, of which the following is a specification.

This invention relates to burglar alarms especially designed for doors, windows and the like and has for an object the provision of an alarm which will be actuated by the opening of a door or window for the purpose of notifying persons in the vicinity of the unauthorized opening of such door or window, the device being useful in residences, outhouses and other buildings.

Another object of the invention is the provision of a burglar alarm which when actuated will discharge a plurality of cartridges, means being provided whereby the cartridges will be fired at intervals so as to more definitely sound the alarm and frighten an intruder.

Another object of the invention is the provision of a burglar alarm of the above type which includes a trigger shaft capable of lateral movement out of the path of the triggers so that the trigger actuating means may be intentionally operated without discharging the cartridges.

With the above and other objects in view, the invention further includes the following novel features and details of construction, to be hereinafter more fully described, illustrated in the accompanying drawings and pointed out in the appended claim.

In the drawings:

Figure 1 is an elevation showing a portion of a door with the invention applied.

Figure 1^a is a similar view showing the device differently arranged.

Figure 2 is a sectional view taken longitudinally through the alarm.

Figure 3 is a section on the line 3-3 of Figure 2.

Figure 4 is a similar view on the line 4-4 of Figure 2.

Figure 5 is a section on the line 5-5 of Figure 2.

Figure 6 is a section on the line 6-6 of Figure 2.

Figure 7 is a detail perspective view of one member of the cartridge holder.

Figure 8 is a similar view of the other member of said holder.

Figure 9 is a detail perspective view of an angular plate used for setting the alarm from the exterior of the building.

Referring to the drawings in detail wherein like characters of reference denote corresponding parts, the reference character 10 indicates a portion of the door of a building, while the door frame is indicated at 11.

By reference to Figure 1 it will be seen that the burglar alarm which is indicated generally at 12 is secured to the door frame to one side of the door and arranged so as to be actuated as the door is opened, as will be later apparent. The alarm includes a casing 13 which is provided with a removable lid or cover 14, whereby access may be had to the interior of the casing. In mounting the casing the lid or cover 14 is provided at opposite ends with brackets 15, from one end of which extend ears 16 having openings for the passage of screws or other fastening devices. From the outer ends of the brackets 15 extend spring tongues 17 whose extremities are provided with offset portions or shoulders 18 adapted for removable engagement with lugs 19 secured to the casing 13. The casing may thus be inserted within the cover 14 and held in place by the tongue 17. The casing is further provided with a gauze or wire covered sight opening 20.

Located within the casing 13 is a block 21 which is provided with a plurality of spaced slots 22, while pivotally mounted beneath this block upon a shaft 23 is a plurality of hammers 24. These hammers move within the slots 22 and are provided with firing pins or points 25.

Mounted upon the block 21 is a cartridge holder which includes a transversely L-shaped member 26. This member is removably held in place by means of screws or other fastening devices 27 which extend through openings 28 provided in the member 26 and engage the block 21. The member 26 is further provided with spaced cartridge receiving openings 29 which are adapted to hold blank cartridges 30. The member 26 may thus be removed and the cartridges inserted within the opening 29 and the said member thereafter replaced. The cartridge holder further includes a plate 31 which is provided with spaced openings 32 adapted to register with the openings 29. This plate engages the end of the cartridge shell and acts to hold the car-

tridge in place, while the openings 32 provide for the passage of the firing pins or points 25. The plate 31 is secured to the block 21 by means of screws or other fastening devices 33 which pass through apertured ears carried by the plate 31.

The block 21 is further provided with a plurality of openings 34 which communicate with the slots 22 and within which are mounted balls or spheres 35. These balls or spheres 35 are forced against the hammers 24 by means of springs 36 so that when the said hammers are moved to the right of Figure 2 of the drawings and released, the springs 36 will act to snap the hammers back against the end of the cartridges so as to fire the latter while the balls or spheres 35 act to reduce friction.

Mounted transversely of the casing 13 and extending through the flange of the lid or cover 14 is a rock shaft 37. This shaft has secured upon its outer end a crank arm 38 which, when the alarm is secured in place will be arranged in the path of opening of the door 10 so as to rock the shaft. The shaft 37 carries a plurality of radially extending fingers or triggers 39. These fingers or triggers are spaced longitudinally along the shaft 38 and are also circumferentially offset or spaced and are located so that when the shaft 37 is rocked they will engage and move the hammers as previously explained so that the said hammers may snap back upon the cartridges. By offsetting the triggers 39, the hammers will be fired consecutively or at intervals.

Mounted upon the shaft 38 are springs 40 which are positioned between the outer triggers 39 and the inner walls of the casing 13, washers 41 being interposed between the walls and the adjacent ends of the springs. The shaft 38 will thus be frictionally and yieldingly held against movement and at

the same time may be manually moved longitudinally so as to permit of its rotation 45 without engaging the hammers.

In order to set the alarm from the outside of a door as in the case where the alarm is used upon a hen house, there is provided an angle plate 42 having a slot 43 therein. 50 This plate is secured to the door frame in such position that one of the ears 16 will enter the slot 43, while the casing is capable of pivotal movement upon the screw which passes through the other ear. By attaching a string to the free ear 16 and passing the same through an opening upon the outside of the building, the door may be closed and the device lowered so that the free ear 16 will enter the slot 43 and the device will 60 be held in place for use.

The invention is susceptible of various changes in its form, proportions and minor details of construction and the right is herein reserved to make such changes as properly fall within the scope of the appended claim. 65

Having described the invention what is claimed is:—

An alarm including a casing, a block in 70 said casing having spaced slots and openings communicating with said slots, a cartridge holder on said block adapted to contain a plurality of cartridges, a hammer for each cartridge, said hammers being pivoted beneath the block and movable in said slots, springs in said openings and bearing against said hammers for normally forcing them toward their respective hammers and means for engaging said hammers for moving them against the tension of said springs whereby said tension will forcibly move said hammers toward the cartridges upon release of said hammers. 75

In testimony whereof I affix my signature.

FRANK J. KOKAL.
